DESIGN FOR AN ARTIFICIAL MINIATURE CHRISTMAS TREE

Charles S. Price, Hollis, N. Y.

Application September 12, 1941, Serial No. 103,321

Term of patent 14 years

To all whom it may concern:

Be it known that I, Charles S. Price, a citizen of the United States, residing at Hollis, in the county of Queens, Long Island, and State of New York, have invented a new, original, and ornamental Design for an Artificial Miniature Christmas Tree, of which the following is a specification, reference being had to the accompanying drawing, forming part thereof, and in which:

Figure 1 is a perspective view of the artificial miniature Christmas tree showing my new design.

Figure 2 is an outer face view of the back part of the ornamental base edging, or that not clearly visible in Figure 1.

The design consists of an artificial miniature

Christmas tree ornamented as shown in the drawing and carrying a duplex star at its top. The vertical line through the center of the star seen in full represents the edge of another similar star combined therewith and extending at right angles thereto, so as to present an appearance similar to that of said first star when viewed from a side.

Otherwise, the portion of the article not shown in Fig. 1 presents substantially the same appearance as that shown in the figure.

I claim:

The ornamental design for an artificial miniature Christmas tree or similar article, substantially as shown and described.

CHARLES S. PRICE.
